UNITED STATES PATENT OFFICE.

CHARLES H. GUNN, OF SALT LAKE CITY, UTAH.

WAGON-BRAKE.

SPECIFICATION forming part of Letters Patent No. 737,098, dated August 25, 1903.

Application filed May 23, 1902. Serial No. 108,723. (No model.)

To all whom it may concern:

Be it known that I, CHARLES H. GUNN, a citizen of the United States, residing at Salt Lake City, in the county of Salt Lake and State of Utah, have invented certain new and useful Improvements in Wagon-Brakes; and I do declare the following to be a full, clear, and exact description of the invention, such as will enable others skilled in the art to which it appertains to make and use the same, reference being had to the accompanying drawings, and to the figures of reference marked thereon, which form a part of this specification.

My invention relates to improvements in wagon-brakes of that class in which the brake-shoes are adapted for engagement with the ground; and its objects are to provide means by which the weight of the wagon will be released from the wheels when the brake is applied and to provide a construction by which the braking action is greatly facilitated by the least exertion of the driver.

With these and many other objects in view, which will readily appear as the nature of the invention is better understood, the same consists in the novel construction, combination, and arrangement of parts hereinafter more fully described, illustrated, and claimed.

The fundamental features of the invention involved in the novel construction and arrangement of parts especially adapting the brake for heavy vehicles are necessarily susceptible to a wide range of modification without departing from the spirit or scope of the invention; but a preferred embodiment is shown in the accompanying drawings, in which—

Figure 1 is a top plan view of the brake applied to the rear axle of the vehicle with the wagon-body removed. Fig. 2 is a vertical section through the rear of the running-gear with the brake applied and showing the wagon-body and operating-levers in side elevation. Fig. 3 is a detail perspective of the hangers for the connection-rod and the clevis connection for the spreader. Fig. 4 is a side elevation showing a modified operating means and the position of the parts when the brake

is released. Fig. 5 is a side elevation of the operating-lever shown in Fig. 4.

Like numerals of reference indicate corresponding parts throughout the several views.

Referring to the drawings, 1 designates the wagon-body mounted on the axle 2, which carries the wheels 3, between which are arranged the mechanism embodying my improved brake. Clamped to the axle are a pair of plates 4, having ears 5, between which are pivotally hung brake-levers 6 6 and the brace-rod 7 7, the former carrying pivotally-mounted shoes 8 at their ends and the latter being bolted or otherwise rigidly secured to the brake-levers to form a substantial connection with the axle. Clamped to the axle are a pair of arms 9 9, in which the rock-shaft 10 is journaled, the said rock-shaft having a crank-arm 11, pivotally connected with a push-bar 12, which extends forwardly and engages the spreader-rods 13 for operating the brake-shoes. The spreader-rod is supported at its front end by the links 14, connected at one end to the reach-bar 15 and at their other ends to the said push-bar. This connection is made by means of a bolt 16, passing through the end of the push-bar, and on which is hung a clevis 17, its lower depending end providing a connection for the spreader-rod 13. Thus the links 14 and clevis 17 form a toggle connection for the push-bar. The ends of the spreader-rods 13 connect with an eye 18 on the end of the cross-bar 19. I prefer to employ a cross-bar provided with coil-springs 21 on each end and which are confined between the shoulders 22 on the cross-bar and the eye 18, so as to provide a yielding action for the spreader-rods when the shoes contact with an obstruction in the road or the wagon-wheels drop into a gulley and cause the shoes to be accidentally thrown to the ground. The eyes 18 are normally held near the ends of the cross-bar 19 by means of the springs 21 and are prevented from being pushed off the bar by means of the pins 20. These eyes are loosely engaged on one side of the cross-bar by rods 23, which connect with the pivoted shoes 8,

and on the other side by the spreader-rods 13, so that when an unusual strain, such as might be caused by an obstruction, is brought on either of the brake-shoes such shoe will be 5 permitted to yield to the strain by virtue of the spring and the jointed connection for the rods 13 and 23 which is made by the eyes 18.

Secured to the bolt 16 are a pair of lifting-rods 25, which play back and forth in eyes 10 26, secured to the inner side of the brake-levers 6. These rods are provided with pins 27, which contact with the eyes 26 when the brake-shoes are lifted from the ground. The brace-rods 7 are connected by a chain 28 to 15 prevent the shoes from spreading and contacting with the wheel of the wagon.

On the end of the rock-shaft 10 is secured a lever 29, having a series of apertures 29^a, to provide an adjustable connection with the 20 rod 30, which is bifurcated at its forward end and through which bifurcation a lever 31 is adapted to oscillate, the said lever being pivoted to the wagon-box, as at 31^a. A lever 32 is connected to the end of the rod 30 and to 25 the lever 31 by a link connection 33. The levers are held in their desired positions by the usual rack-bar 34, which is in the present instance formed of a single piece. By this construction the brake must first be applied 30 by the lever 31, and when the lever 32 is pushed forward a further pressure is imparted to the brake and the wagon lifted from its wheels. The rod 30 throws the lever 29 forward, rocks the shaft 10, which swings the 35 toggle connection of the clevis and links 14 forward, increasing the distance between the brake-shoes and the toggle connection, causes the cross-bar 19 to be pulled forward, and by the connecting-rods 23 forces the brake-shoes 40 in contact with the ground. When the above operation is reversed, the pins 27 on the rod 25 will engage the eyes 26 on the levers 6 to lift the shoes from the ground. When either shoe contacts with an obstruction, the coil-spring 45 on the cross-bar 19 will be compressed to increase the distance between the ends of the spreader-bars and the rocking shaft 10 without affecting the other parts or causing the operating-levers 29, 31, and 32 to be displaced from their normal positions, so that 50 the brake-shoe will immediately assume its former position when it has passed over the obstruction.

In Figs. 4 and 5 I have shown a modified 55 form of operating mechanism in which an operating-lever 35 is pivoted to a yoke 36, carrying a drum 37, around which an operating-rope 38 passes and connects at each end with the lever 29. On each side of the drum are 60 ratchets 39, adapted to be engaged by pawls 40 and 40^a, pivoted on each side of the lever 35. The pawl 40 is normally held in engagement with its ratchet by a spring 41 and adapted to be disengaged therefrom by means of a

rod 42, which extends into engagement with a 65 lever 43, pivoted to the operating-lever 35. When the brake is not applied, the parts assume the position shown in Fig. 4, and when the lever 35 is thrown forward the pawl 40 will engage its ratchet and wind the upper 70 portion of the rope on the drum. This will pull the lever 29 forward to the position shown in Fig. 2 and apply the brake. When the lever is forward and the brakes applied, a lever 42^a, having an arm 43^a, is pushed forward 75 by the driver's foot to hold the pawl 40^a in engagement with its ratchet and prevent the lever 35 from falling back.

This brake is more particularly adapted for heavy wagons used in mountainous countries, 80 and especially in mining districts. When the wagon is loaded with ore, the enormous load cannot be held back with the old form of brake; but my improved brake enables the rear wheels of the wagon to be lifted from the 85 ground with slight exertion on the part of the driver and the axle-skein and tires of the wheels are not worn by the constant scraping. The yielding connection between the 90 push-bar 12 and the brake-shoes permits the shoes to adjust themselves to the unevenness of the ground, so that an obstruction to one will not affect the other.

Having thus described my invention, what I claim is—

1. A vehicle-brake consisting of brake-levers supported from the axle and having brake-shoes mounted thereon, a push-bar, spreader-rods depending from the push-bar, a cross-bar supported by the spreader-rods, 100 rods connecting the push-bar and the shoes, and means on the cross-bar to permit each shoe to yield independently of the other.

2. A vehicle-brake consisting of brake-levers supported from the axle and carrying 105 pivoted shoes, a push-bar, a cross-bar having coil-springs and eyes mounted thereon, spreader-bars depending from the end of the push-bar and connected to the eyes on the cross-bar, rods connecting the eyes and the 110 shoes, whereby the shoes are permitted to adjust themselves to the unevenness of the ground.

3. In a vehicle-brake, the combination with 115 brake-levers carrying brake-shoes, of a rock-shaft having a lever mounted thereon, levers mounted on the wagon-body for operating the brake, a rod connecting the operating-levers and the rock-shaft lever, a push-bar, a link connection to support the end of the said 120 push-bar, a cross-bar, spreader-rods connecting the cross-bar with the push-bar, and shoe-lifting rods engaging the brake-levers and the push-bar.

4. In a vehicle-brake, the combination of 125 brake-levers pivotally supported from the axle and having shoes pivoted thereto, a push-bar, a cross-bar, a jointed connection for the

push-bar and cross-bar, a link connection between the wagon and the end of the push-bar, rods 23 for bringing the shoes into operative position, shoe-lifting rods connected to the 5 push-bar and having a loose connection with the brake-levers, means to permit each brake-lever to act independently of the other, a rock-shaft having a lever, operating-levers mounted on the front of the wagon and a connection

between the operating-levers and the rock-shaft.

In testimony whereof I affix my signature in presence of two witnesses.

CHARLES H. GUNN.
